UNITED STATES PATENT OFFICE.

EUGENE J. FARKAS, OF DETROIT, MICHIGAN, ASSIGNOR TO FORD MOTOR COMPANY, OF DETROIT, MICHIGAN, A CORPORATION OF DELAWARE.

COMBINED FUEL VALVE AND SEDIMENT BULB.

Application filed October 8, 1920. Serial No. 415,529.

To all whom it may concern:

Be it known that I, EUGENE J. FARKAS, a citizen of the present domain of Hungary, having applied for and received my first 5 papers for naturalization in the United States, residing at Detroit, in the county of Wayne and State of Michigan, have invented new and useful Improvements in a Combined Fuel Valve and Sediment Bulb, of 10 which the following is a specification.

The object of my invention is to provide new and useful improvements in a combined fuel valve and sediment bulb of simple, durable, and inexpensive construction.

15 A further object of my invention is to provide a device adapted to form a common sediment bulb for two tanks of different kinds of fuel thereby eliminating, as far as possible, duplicate sediment bulbs and fuel lines with the consequent tendency of additional parts to get out of order.

20 A further object of my invention is to provide a valve adapted to control the supply of fuel to the carburetor so that the engine, operated from the carburetor, may be operated upon either of two different kinds of fuel or the fuel may be cut off entirely.

25 A further object of my invention is to provide an improved two-way valve especially adapted to co-operate with fuel inlet ports and a sediment chamber, the arrangement being such as to allow fuel from either of the two ports to reach the sediment chamber.

30 35 A further object of my invention is to provide a sediment bulb or casing, having fuel inlets and outlets therefrom which are so arranged that fuel passing through the bulb to the carburetor must pass through a 40 screen or strainer, and which is so arranged that either of two kinds of fuel, when fed into the bulb, just pass through this strainer.

45 A further object of my invention is to provide a drain valve or plug, which is so arranged that it may drain the fuel and sediment from the portion of the interior of the casing which is enclosed by the screen.

50 A further object of my invention is to provide an improved mounting for the screen whereby it may be readily removed for cleaning and inspection when desired.

55 A further object of my invention is to provide a casing which may communicate directly with one of said tanks.

With these and other objects in view, my

invention consists in the arrangement, combination, and construction of the various parts of my improved device, as described in the specification, claimed in my claims, and shown in the accompanying drawings, 60 in which

Figure 1 is a transverse vertical sectional view through a fuel tank construction and showing an elevation of my improved combined sediment bulb and fuel valve. 65

Figure 2 is a side elevation of my improved valve, and

Figure 3 is a vertical central sectional view through the casing of my improved sediment bulb and fuel valve. 70

Referring to the accompanying drawings, I have used the reference number 10 to indicate, generally, a fuel tank which is substantially oval in cross section and provided with a plurality of baffle plates 11, 75 designed to prevent the fuel in the tank from undue washing back and forth within the tank due to the movement of the latter. Mounted within the tank 10 and enclosed thereby is a second fuel tank 12, having a 80 filler opening 13 and an outlet opening 14. The tank 10 has an outlet opening 15.

It will be understood that the fuel tanks 10 and 12, are designed to be used where an internal combustion engine may be driven 85 by either of two fuels, such, for instance, as gasoline and kerosene. In such a case the gasoline would be placed within the tank 12 and the kerosene within the larger tank 10.

90 For conducting the fuel from the tank 12 I provide the following mechanism:

The outlet opening 14 of the tank 12 is countersunk somewhat at 16 and a registering opening 17 is provided in the bottom 95 of the tank 10. A gland 18 has a flange at one end thereof received in the countersunk portion 16 and the body thereof extended through the openings 14 and 17. A nut 19 is screwed on to the body portion of the 100 gland 18, outside of the tanks, in such a position that the webs of the tanks 10 and 12, around the openings 14 and 17 therein, will be gripped between the nut 19 and the flange of the gland 18 when the nut is tightened, thereby insuring a fluid-tight connection between the tanks 10 and 12 and the gland 18. Threaded into the gland 18 is a 105 pipe 20 which runs into an elbow 21, which in in turn connects with a fuel pipe 22, the 110

latter being connected into a friction or expanding joint 23. From the connections just described it will be seen that fuel may be removed from the tank 12 without it coming in contact with the fuel in the tank 10, or without there being danger of the fuel being lost through leakage.

Around the opening 15 in the tank 10 a flange 15^a is riveted, this flange being provided with a threaded opening 24.

My improved combined sediment bulb and valve comprises a casing A, having in the bottom thereof a relatively large recess 25 adapted to form a sediment pocket, and in the upper central portion thereof, a substantially cylindrical recess 26 adapted to form a valve casing. Extending upwardly from the portion of the casing around the recess 26 is a nipple 27 which is externally screw-threaded and has a central opening or port 29 therein designed to communicate with the recess 26. This nipple 27 is screwed into the flange 23 on the tank 10 to form a fluid-tight joint with the tank so that fuel from the tank may pass down into the recess 26. A similar nipple 28 projects laterally from the upper portion of the casing "A" and also has a central opening or port 30, which communicates with the recess 26. This nipple 28 is designed to communicate with the friction joint 23 at the end of the pipe 22, and to form a liquid-tight joint therewith.

From the description of the foregoing parts it will be seen that fuel may be supplied to the recess 26 through the opening 29 in the nipple 27, from the tank 10, or through the opening 30 in the nipple 28 from the tank 12.

Mounted within the recess 26 is a substantially cylindrical valve member 31 having T shaped opening 32 therein.

Referring to the Figure 3, it will be seen that when the valve 31 is in a position shown, then that fuel cannot enter the recess 26 from either the openings 29 or 30. If, however, the valve be rotated one-eighth of a turn in a clockwise direction, then that the fuel may enter the recess 26 and pass through the valve from the port 30, this fuel flowing through the opening 32 through one end of the long portion thereof and through the short arm thereof. The recess 26 is connected with the sediment pocket 25 by a passageway 33, and when the valve is moved to the position stated it will be seen that the short arm of the passageway 32 will register with this opening 33 so that the fuel received from the port 30 will pass into the sediment bulb pocket 25. If, however, the valve be rotated in a counter-clockwise direction back to the position shown in Figure 3 and then another one-eighth turn, it will be seen that the long portion of the opening 32 will connect the

port 29 with the passageway 33, so that the fuel from the opening 29 will be fed into the sediment pocket 25. The rotation of the valve from the position shown in Figure 3, in either direction will, therefore, permit fuel to be fed from either of the tanks 10 or 12, selectively.

The bottom of the sediment pocket 25 has a relatively large threaded opening 34 therein, designed to receive the plug 35. The latter has a central opening therein which is comparatively wide at its upper portion 36, contracted to form a valve seat 37 intermediate of its ends, and threaded at 38 to permit a valve 39 to be screwed into that portion of the plug. The valve 39 is so arranged that when it is screwed up tight it will completely close the valve opening 37, and when it is unscrewed then that the liquid within the sediment pocket may escape through the valve opening 37.

Extending from the top to the bottom of the sediment pocket 25 is a cylindrical screen member 40, which is fastened to the plug 35 within the recess 36. At the top of the screen or strainer 40, the flange 41 is secured, this being designed to enter and fit closely into a pocket 41 at the top of the recess 25 and around the passageway 33.

A nipple 42 extends laterally from the casing adjacent to the upper part of the sediment pocket 25 and is provided with a screw threaded end portion 43, and a central opening 44, designed to form an outlet port for the sediment pocket.

From the construction of the parts just described it will be seen that fluid admitted into the sediment pocket 25 through the passageway 33, will flow down into the interior of the cylindrical strainer 40. It may then pass through the strainer and out of the sediment pocket, adjacent to the top thereof, through the outlet port 44. When desired, however, the valve 39 may be unscrewed to drain the sediment pocket thereby draining out such impurities as may have been strained out of the fuel by the strainer 40. If it is desired to clean the sediment pocket thoroughly, for any reason, or to clean the strainer cylinder, then the plug 35 may be unscrewed thereby removing the strainer 40, so that it may be washed in any desired manner. In this connection it may be mentioned that the strainer 40 may, if desired, be stiffened with any suitable means so that when the plug 35 is screwed into the sediment pocket then the flange 41, at the upper end of the strainer, may be forced into the recess 41^a to thereby form a substantially liquid-tight joint between the flange and the recess. This engagement must, however, be so arranged that it will not interfere with the forming of the liquid-tight joint between the plug 35 and the casing A.

The nipple 42 is connected by suitable feed lines with the carburetor in an internal combustion engine and it will be seen that when the parts are so arranged, then that 5 the valve 31 may be operated to feed through the nipple 42 either of the fuels in the tanks 10 or 12, or to cut off the fuel from the nipple 42 altogether.

For operating the valve 31 I provide the 10 following mechanism: It will be understood that the valve 31 is rotatably mounted within the recess 26 and I preferably make the body of the valve somewhat tapered, as is indicated by the dotted lines 45 and 46 15 in Figures 1 and 3, and taper the recess to correspond. A stem 47 projects from the body of the valve 31 and has an operating arm or lever 48 screwed to the outer end thereof. Encircling the stem 47 between 20 the casing A and the lever 48 is a spring 49, which tends to yieldingly draw the valve 31 through the recess 26, thereby drawing the tapered portions of the valve 31 and recess 26 into closer engagement. The lever 25 48 is provided with laterally extending ears 50 at either side thereof, which are designed to contact with the stop 51 which extends outwardly from the casing A into the path of these lugs 50, so that contact of either 30 of these ears with the corresponding side of the stop 51 will limit the movement of the lever 48 to properly position the valve 31 so that liquid may pass therethrough from either port 29 or port 30. In the form 35 of valve here shown the vertical position of the arm 48 is the closed position of the valve so that no stop is necessary for the closed position. At the bottom of the lever 48 is an opening 52 designed to receive an 40 operating rod 53, which may be extended to any suitable place to thereby permit the operation of the valve 31 from the most convenient position for the operator.

Among the many advantages arising from 45 the use of my improved device it may be mentioned that I am enabled to dispense with an extra sediment bulb and also with a special casing and bracket or other mounting for a fuel valve. By eliminating a large 50 amount of the fuel line material which has been used in the past I am enabled to minimize the danger of leakage and other troubles from a fuel supply system. By placing the tank 12 within the tank 10 and by 55 the relation of the parts, as shown, I am

enabled to economize on space, material and ease of manufacture, and at the same time insure liquid tight joints.

Some changes may be made in the arrangement and construction of the various parts 60 of my improved device without departing from the spirit of the invention therein and it is my intention to cover by my claims such changes as may be reasonably included within the scope thereof. 65

I claim as my invention:

1. In a device of the class described, the combination with a main fuel feeding tank, of an auxiliary fuel tank seated within said main tank, independent outlet openings 70 from each of said tanks, a combined fuel strainer and shut-off valve in connection with the tank comprising a casing carried by said main tank and having a fuel inlet leading thereto from each tank, a single 75 fuel outlet leading from the casing, a valve in said casing, means for adjusting said valve to admit fuel from either the main or auxiliary tank to the interior of said casing, a strainer disposed beyond said valve 80 and from which fuel must pass, a removable closure in the bottom of the casing through which sediment that is separated from the fuel is discharged, and an outlet port leading from said casing through which fuel 85 passes after traveling through said strainer.

2. In a device of the character described, the combination with a main fuel feeding tank, of an auxiliary tank disposed therein, fuel feeding openings through each tank, 90 a strainer and control valve supported by said main tank comprising a casing, independent inlets to said casing communicating with said main and auxiliary tanks, a two-way valve disposed within the casing, said 95 valve being movable to permit the entrance of fuel to the interior of the casing from either of said fuel tanks, said casing having an opening therein below said valve, a strainer mounted in said opening, a removable base on which said strainer rests detachably connected with said casing, a removable sediment plug carried by said base beneath said strainer, and a fuel discharge opening leading from said casing beyond 105 said strainer.

EUGENE J. FARKAS.
